UNITED STATES PATENT OFFICE.

WILLIAM MOLLE, OF OSHKOSH, WISCONSIN.

TABULATOR-STOP FOR TYPEWRITERS.

1,400,492.

Specification of Letters Patent. Patented Dec. 13, 1921.

Application filed October 15, 1920. Serial No. 417,090.

To all whom it may concern:

Be it known that I, WILLIAM MOLLE, a citizen of the United States, residing at Oshkosh, in the county of Winnebago and State 5 of Wisconsin, have invented a new and useful Tabulator-Stop for Typewriters, of which the following is a specification.

This invention relates to typewriters and more especially to tabulator rails and stops, 10 one of the objects of the invention being to provide a substantial tabulator rail on which a scale is displayed, there being a tabulator stop adjustably mounted on the rail and carrying a pointer which coöperates with the 15 scale on the rail to give the exact position of the stop with relation to the front paper holder scale whereby the operator may set the stop accurately for any desired position on the paper.

20 A further object is to provide a tabulator stop which is of rigid construction, is simple and durable, which can be firmly locked in any desired position on the tabulator rail and which, when released, will slide freely 25 along the rail.

A further object is to provide a tabulator stop having a pointer projecting therefrom where it can be seen conveniently above the graduated scale on the rail, the said pointer 30 constituting means for preventing the parts of the stop from becoming separated as long as the stop is in position on the rail.

With the foregoing and other objects in view, which will appear as the description 35 proceeds, the invention resides in the combination and arrangement of parts and in the details of construction hereinafter described and claimed, it being understood that, within the scope of what is claimed, changes in the 40 precise embodiment of the invention shown can be made without departing from the spirit of the invention.

In the accompanying drawings the preferred form of the invention has been shown.

45 In said drawings—

Figure 1 is a perspective view of a portion of a tabulator rail and showing two stops in position thereon, one of the stops being locked and the other unlocked.

50 Fig. 2 is a plan view of one of the stops and the adjacent portion of the rail.

Fig. 3 is a perspective view of the body member of the stop.

Fig. 4 is a perspective view of the locking member of the stop. 55

Fig. 5 is a side elevation of the body member of the stop.

Fig. 6 is a detail view of the blank from which the body member is shaped.

Referring to the figures by characters of reference 1 designates a tabulator rail on one face of which are provided ratchet teeth 2 while on the top of the rail are arranged graduations 3 forming a scale. The stop used on the rail includes a body formed of a 60 plate 4 having a depending tongue 5 which can be formed with an opening 6 to receive the screw of the bell cam not shown. A pointer or index 7 is extended from the upper end of the plate 4 and extending from the sides of the upper portion of the plate are parallel wings 8 each of which has an angular opening 9 through which the rail 1 is adapted to extend.

Slidably mounted on the plate 4 and between the wings 8 is a locking plate 10 having a longitudinal slot 11 through which the pointer or index 7 projects. Extending from the upper end of the locking plate is a 70 finger piece 12 and flanges 13 are formed 80 along the sides of this plate 10 and are adapted to slide along the inner faces of the wings 8.

It is to be understood that under normal 85 conditions the locking plate 10 is in its lowest position with its finger piece 12 resting on the top of the plate 4 and with the flanges 13 projecting between certain of the teeth 2. By lifting upwardly on the finger piece 12, however, the plate 10 can be raised 90 so as to withdraw the flanges 13 from engagement with the teeth 2 whereupon the stop can be moved freely to any position desired and then again locked by lowering the plate 10. It will be noted that the index 95 or pointer 7 extends through the slot 11. Thus it becomes impossible to separate the parts 4 and 10 as long as the rail 1 is in position within the openings 9. This index or pointer 7 laps the graduated face of the rail 1 so as to indicate a selected graduation.

Furthermore the flanges 13 on the locking piece 10 are wedge shape, and the angular opening 9 in the wings on the sides of the stop are also cut on an angle with the back 105 surface 4 of the stop, the object being that

the harder the locking piece 10 is forced down, the tighter the stop and rail will be locked together, entirely doing away with all side play which is so objectionable in a 5 tabulator stop.

What is claimed is:—

1. The combination with the tabulator rail of a typewriter having a toothed face, of a stop adjustable along the rail, a pointer 10 projecting from the stop, a locking member 15 slideable on the stop and held assembled therewith by the pointer, and means on said member for engaging the toothed face of the rail to hold the stop against movement upon the rail.

2. The combination with the tabulator rail of a typewriter having a toothed face, of a stop including a member having wings provided with openings through which the 20 rail extends, a locking member movably mounted between the toothed face of the rail and the first named member, means thereon for engaging the adjacent teeth on the rail to hold the members against movement along the rail.

3. The combination with the tabulator rail of a typewriter having a toothed face, of a stop including a member having wings provided with openings through which the 30 rail extends, a locking member movably mounted between the toothed face of the rail and the first named member, means thereon for engaging the adjacent teeth on the rail to hold the members against movement along the rail, and a finger piece extending from the tooth engaging member and normally bearing upon one end of the apertured member.

4. The combination with the tabulator 40 rail of a typewriter having a toothed face,

of a stop including a member having wings provided with openings through which the rail extends, a locking member movably mounted between the toothed face of the rail and the first named member, means 45 thereon for engaging the adjacent teeth on the rail to hold the members against movement along the rail, and a pointer upon one of the members for holding both members assembled while in operative position with 50 the rail.

5. The combination with the tabulator rail of a typewriter having a toothed face, of a body member having apertured wings through which the tabulator rail extends, a 55 locking member slideable between the body member and the toothed face of the rail and having a tooth engaging portion, a finger piece extending from the locking member and beyond the body member.

6. The combination with a tabulator rail of a typewriter having a toothed face, of a body member having apertured wings through which the tabulator rail extends, a locking member slideable between the body 65 member and the toothed face of the rail and having a tooth engaging portion, a finger piece extending from the locking member and beyond the body member, said locking member having a longitudinal slot, and a 70 pointer extending from the body member and through the slot for holding the members assembled while in position on the rail.

In testimony that I claim the foregoing as my own, I have hereto affixed my signature in the presence of two witnesses.

WILLIAM MOLLE.
